UNITED STATES PATENT OFFICE.

SOLON P. HAUN, OF MOHAWK, TENNESSEE.

ACETYLENE-GAS GENERATOR.

1,231,155.

Specification of Letters Patent. Patented June 26, 1917.

Application filed February 28, 1917. Serial No. 151,094.

To all whom it may concern:

Be it known that I, SOLON P. HAUN, a citizen of the United States, residing at Mohawk, in the county of Greene and State of Tennessee, have invented certain new and useful Improvements in Acetylene-Gas Generators; and I do declare the following to be a full, clear, and exact description of the invention, such as will enable others skilled in the art to which it appertains to make and use the same.

This invention relates to new and useful improvements in acetylene gas generators and the primary object of the invention is to provide a generator of this type that is automatically operated to control the amount of gas formed thereby.

Another object of this invention is to provide a device of this character which is provided with a safety attachment whereby any excess volume of gas that is formed in the generator may be easily carried off without any danger, or in any way interrupting the operation of the device when the gas pressure has returned to normal.

Still another object of this invention is to provide an acetylene gas generator of this character which is provided with means for lifting and holding a carbid hopper that is disposed on the top of the gas bell in raised position, so that the same may be easily refilled.

A further object of the invention is to provide a device of this character which is simple and durable in construction, inexpensive to manufacture, and one which will be very efficient in operation.

With these and other objects in view, the invention consists of the novel features of construction, and the combination and arrangement of parts which will be herein-after referred to and more particularly pointed out in the specification and claims.

The accompanying drawing represents a central vertical section of the tank, bell, and carbid hopper of my invention, showing also the pipe frame and accessories in elevation.

In describing my invention I shall refer to the drawing in which the numeral 1 designates the water tank of my improved generator which may be of any desired shape and which is formed preferably with downwardly sloping side portions 2 which have secured thereto and projecting upwardly an annular portion 3 that forms between the edge of the tank and the same the conven-

tional type of water seal that is commonly used in devices of this character.

The water tank 1 is provided with a sloping bottom 4 which has at its lowermost point an outlet 5 through which the water may be easily drained when it is desired to empty the tank. This outlet 5 is provided with any type of valve as clearly shown in the drawings.

Positioned through one side of the inwardly projecting side portions 2 of the water tank is an agitator 6 which comprises a rod 7 having a handle 8 at its outer end, the said rod being positioned through a sleeve or casing 9 that projects upwardly from the tank. Secured to the lower end of the rod 7 is any desired type of agitator 10. By the above described construction, upon movement of the handle 8, the rod 7 will be rotated and consequently the agitator 10 secured to its lower end will stir the contents of the tank.

The water tank 1 is provided with a transversely extending pipe 11 that has its opposite ends projecting from the said tank, and connected with the opposite ends of this pipe are vertical upright parallel pipes which are designated by the numerals 12 and 13. These pipes 12 and 13 have their lower ends secured to the projecting ends of the transversely extending pipe 11 by suitable connections. The pipe 13 will be called the service pipe and the pipe 12 the excess volume outlet pipe as they perform the aforesaid functions.

The pipes 11 and 12 have positioned in the upper ends of the same plugs 14 to prevent gas escaping through the pipes. The upper ends of these pipes are connected by a cross member 15 which comprises two sections having their ends connected by a cross coupling 16. The ends of these pipes are joined by suitable L-connections and the pipes when assembled will form a frame for the generator. The vertical upright pipes 12 and 13 are connected with the portions 3 of the outer wall of the water seal by brackets 17.

Arranged within the water tank and projecting centrally and upwardly from the transverse pipe 11 is a gas pipe 18. This gas pipe 18 extends upwardly and outwardly at right angles thereto and then upwardly to a point above the water level of the tank. This pipe forms a connection between the gas generator and carries the gas to the transverse pipe 11 by which means

it is carried from the tank. The branch inlet pipe 18 is provided at its first angle with a flat head 19 for a purpose to be hereinafter more fully described.

- 5 The generator is provided with the usual type of gas bell 20 that has its lower edges positioned in the water seal and the bell is vertically movable with respect to the tank. Secured in the upper end of the gas bell is 10 a carbid hopper 21 which has its lower portion substantially cone-shaped with an open lower end. Positioned within the carbid hopper 21 is a valve 22 that has a vertically movable stem 23 guided within the hopper by brackets 24. The lower end of the stem 23 projects downwardly below the open end of the hopper and has a weight 25 positioned on its extremity. The stem 23 is disposed in vertical alinement with the central 15 portion of the branch inlet pipe 18 and the extremity of the stem is adapted for engagement with the head 19 of this portion. The upper end of the carbid hopper is provided with an inlet which is used for filling the 20 same. Projecting upwardly from the top of the carbid hopper 21 is a vertically upright stem 26 which is slidably positioned through the cross coupling 16 of the cross pipe 15 that connects the upper ends of the 25 service and outlet pipes. Upon movement of the gas bell, this stem will slide within the cross coupling and will act as a guide for the bell and hopper. An eye 27 is disposed on the end of the stem for a purpose 30 to be hereinafter more fully described.

Projecting upwardly from one of the sections of the cross pipe 15 is a standard 28 that has a lever 29 fulcrumed at its upper end. This lever 29 is provided with a hook 30 on one end and a handle 31 on the other, and the hook 30 is so disposed that it is adapted for engagement with the eye 27 on the stem 26. The fulcrumed lever 29 has an additional hook 32 which provides means 35 whereby the lever may be locked in raised position. When it is desired to lift the gas bell and carbid hopper out of the tank, the fulcrumed lever is lowered and the hook at the end of the same is engaged with the eye 40 on the upper end of the stem. Upon raising the lever, the gas bell and hopper will be raised and they may be locked in this position by the locking means 32 on the lever. The hopper may then be easily filled with 45 fresh carbid.

The service pipe 13 is provided with an outlet branch 33 that has disposed intermediate its ends a filter 34. The gas generated within the bell is normally carried through 50 the pipe 18 and the transverse pipe 11, and hence through the service pipe and its outlet to any desired place.

The excess volume pipe 12 is provided intermediate its ends with a valve 35 which 55 valve is operated by a crank 36. Projecting

laterally from the hopper 21 is a rod 37 and the outer end of the rod is connected with the crank 36 by a chain 38. By this connection and owing to the fact that the valve 35 is normally closed, upon the hopper being elevated by the gas bell when an excessive amount of gas is formed in the bell, the hopper will consequently be raised to an unusual height and by the above described connection the crank 36 will be operated 70 and the valve opened. The excess volume of gas may then escape through the transverse pipe 11, the outlet pipe 12 and off through a discharge 39 on said pipe. As soon as the gas within the bell returns to 75 normal, the bell and hopper will drop and the valve will return to closed position.

In operation, when the carbid hopper 21 is full, the lower end of the stem of the valve will engage the head 19 of the vertical gas inlet pipe, and the valve will be opened and the carbid fed into the water tank to generate the gas. As the gas forms within the bell, the same will rise slowly and when an excessive amount is placed 80 therein, owing to the fact that the valve from the carbid hopper is held stationary by its weighted stem, when the bell and hopper rise, the flow of carbid will be cut off automatically. This will prevent a further generation of gas until that within the tank has been carried off by the discharge pipes. If, for any reason, the valve should not work and the gas should still be generated within the bell, the same will rise to 85 an excessive height and the safety valve will be opened as has been hereinbefore described and the gas will not only be carried through the service pipe but it will also be carried out through the excess volume outlet pipe and discharged.

The agitator used in the water tank forms a very simple means for preventing sediment from gathering in the bottom thereof and owing to the fact that this tank is provided 90 with a sloping bottom and an outlet at its lower end, the same may be easily drained. The connected pipes that form the frame around the gas bell and hopper are of any proportional size and are connected in any 95 desired manner. These pipes are provided with plugs at the upper ends of the vertical pipes so that the gas will not enter the upper cross pipe. The transverse pipe within the tank that is connected with the pipe 18 100 that is disposed within the tank and bell, forms a discharge and gas flows therethrough one way to the service pipe and the other to the excess volume pipe.

From the foregoing description of the 105 construction and operation of my improved acetylene gas generator, the manner of applying the same to use and the operation thereof will be readily understood, and it will be seen that I have provided a simple 110

and efficient means for carrying out the objects of the invention.

I claim:

1. A device of the character described comprising a tank, a gas bell disposed above the same, a water seal between said tank and bell, a transverse pipe extending across the tank and projecting from the sides thereof, vertically disposed service and excess volume outlet pipes having their lower ends connected to said pipe and extending to a point above the gas bell, a branch gas pipe arranged in said tank and connected at its lower end to the transverse pipe, a cross member connecting the upper ends of said outlet and service pipes composed of two sections connected by a cross shaped coupling, outlets for said outlet and service pipes below the junction of said pipes with the said cross member, plugs in the upper ends of said pipes above the outlets therein, a carbide hopper on the upper end of said gas bell, and means extending upwardly from said hopper and slidably engaged with the coupling for locking said hopper in raised position, an upwardly projecting standard on one section of said cross member, a lever fulcrumed at the upper end of said standard, a detachable connection between one end of said lever and the upper end of the stem, and means to lock the lever in raised position.
2. In a device of the class described, a

tank, a bell above said tank, a vertically movable hopper mounted on said bell, and a valve in said hopper provided with a stem depending into said tank; together with means for guiding said hopper in its vertical movement and for automatically opening the valve in said hopper at a certain predetermined position of said hopper, said guiding and operating means comprising a transverse discharge pipe extending entirely across the interior of the tank and having its ends extending beyond the outer edges thereof and provided with an upwardly extending centrally disposed inlet having a flat portion adapted to contact with said hopper valve and operate the same, vertically disposed service and excess volume outlet pipes having their lower ends connected to said pipe and extending to a point above the gas bell, a cross pipe connecting the upper ends of said pipes, a stem projecting upwardly from said hopper and guided through the upper cross pipe, plugs in the upper ends of the service and outlet pipes, an outlet for said service pipe, and a discharge for the excess volume outlet pipe.

In testimony whereof I have hereunto set my hand in the presence of two subscribing witnesses.

SOLON P. HAUN.
